COMBINATION LOCK STRIP AND
STRUCTURAL MEMBERRobert M. Brown, Kansas City, Kans., assignor to
Emile S. Guignon, Jr., Kansas City, Mo.

Application November 9, 1942, Serial No. 464,976

3 Claims. (Cl. 20—4)

This invention relates to structural members for portable buildings and has for its primary aim to provide a combination lock strip and structural member which cooperates with specially formed building units in maintaining a wall or the like in assembled condition without the use of framework or other stress receiving elements.

Another object of this invention is to provide a portable building structure having as a part thereof a series of units arranged in edge-to-edge relation and a lock strip contoured to cooperate with the formed edges of the units in maintaining the parts in normal position.

This invention has for an even further object to provide a lock strip for building units, the character of which insures progressively drawing together the abutting edges of the units as the lock strip is moved to normal place.

Specific details of construction, and particularly the manner of forming both the edges of the building units and the lock strip constitute further objects of the invention, and such details will be clarified during the course of the following specification referring to the accompanying drawing wherein:

Fig. 1 is a fragmentary perspective detailed view illustrating in a stretched out condition, a combined lock strip and structural member made in accordance with the present invention; and

Fig. 2 is a fragmentary edge view through a joint formed between two abutting building units and the lock strip forming a connection therebetween.

The units, broadly designated by the numeral 6, are of conventional form and have the abutting edges thereof contoured as illustrated, to present an L-shaped offset, two faces 8 and 10 respectively whereof, are undercut or disposed at an angle for the purpose of frictionally engaging angled faces 12 and 14 respectively, of the combined structural member and lock strip 16.

The face 8 is intermediate the major planes of the outer surfaces of unit 6 and the edge of the unit lying between one of the major surfaces 18 and face 8, is angled outwardly from the outer edge of face 8 to present an inclined surface 20.

Member 16 is T-shaped in cross section and has a longitudinal groove 22 formed along the web thereof to engage faces 8 as shown in Fig. 2. The opposed longitudinal edges 24 of member 16 are inclined to diverge from their line of meeting with angled faces 14, and when these said inclined faces 24 lie in opposed relation to the proximal edges of units 6, the outer portion of strip 16 is closer to the edges of the abutting units

5 than the inner portions thereof—this due to the fact that the edges of unit 6 opposed to inclined faces 24 are in parallel relation and substantially perpendicular to the major plane of the units.

The width of the web of unit 16 is less than the distance between the edges of units 6 between faces 8 and 10 formed on the shoulders of the edges of the units created by the L-shaped offset in each.

When units 6 are in abutting relation, a T-shaped groove is established for the reception of structural member 16. The inclined surfaces 20 will abut as shown, with the outermost portions thereof in close proximity while the innermost portions are slightly spaced apart. Likewise faces 24 will be inclined with respect to the directly opposed marginal edges of units 6, and when tie-members 26 are positioned and tightened, units 6 will be drawn together and against faces 24 of member 16 to insure a very tight joint.

Tie-members 26 should be positioned to permit movement of units 6 toward each other and as above mentioned, the width of the web portion 28 of structural member 16 should be less than the distance between the opposed edge surfaces of units 6 to allow inward movement due to the engagement between the aforesaid inclined surfaces of both the units and tie-member 6 and 16 respectively.

This tie-member 16 may be first set up in a building to be a load bearing member and thereafter units 6 secured thereto to create a tight joint.

Having thus described the invention, what is claimed as new and desired to be secured by Letters Patent is:

1. In a portable building, a plurality of units arranged in edge-to-edge relation; and a combined lock strip and structural member at the meeting edges of said units, said units each having a pair of undercut shoulders, said strip being T-shaped in cross section and having a central web provided with a longitudinal groove to simultaneously receive one undercut shoulder of each of a pair of adjoining units, said strip having a head portion provided with opposed inclined faces converging toward said web for respectively engaging the remaining undercut shoulders of adjoining units.

2. In a portable building, a plurality of units arranged in edge-to-edge relation; and a combined lock strip and structural member at the meeting edges of said units, said units each having a pair of undercut shoulders, said strip being

T-shaped in cross section and having a central web provided with a longitudinal groove to simultaneously receive one undercut shoulder of each of a pair of adjoining units, said strip having a head portion provided with opposed inclined faces converging toward said web for respectively engaging the remaining undercut shoulders of adjoining units, the width of the head of said strip at its outer face being greater than at the inner face thereof, whereby to establish tighter engagement between the proximal units and the strip at the outer face of the latter than at the inner face thereof.

3. In a portable building, a plurality of units arranged in edge-to-edge relation; and a combined lock strip and structural member at the meeting edges of said units, said units each having a pair of undercut shoulders, said strip being T-shaped in cross section and having a central web provided with a longitudinal groove to simul- 15

aneously receive one undercut shoulder of each of a pair of adjoining units, said strip having a head portion provided with opposed inclined faces converging toward said web for respectively engaging the remaining undercut shoulders of adjoining units, the width of the head of said strip at its outer face being greater than at the inner face thereof, whereby to establish tighter engagement between the proximal units and the strip at the outer face of the latter than at the inner face thereof, said shoulders being between the two major surfaces of the units, the opposing surfaces of the unit edges between one major surface of the units and said shoulders engaged by the web of said strip being oppositely inclined to space said shoulders from each other when the edges of the units along the one said major surface are in contiguous relation to each other.
